UNITED STATES PATENT OFFICE.

HESSY S. ROSENSTOCK, OF BALTIMORE, MARYLAND.

DESIGN FOR A KNIFE AND FORK POLISHER.

SPECIFICATION forming part of Design No. 24,466, dated July 16, 1895.

Application filed June 18, 1895. Serial No. 553,236. Term of patent 7 years.

To all whom it may concern:

Be it known that I, HESSY S. ROSENSTOCK, a citizen of the United States, residing at Baltimore, in the State of Maryland, have invented and produced a new and original Design for a Knife and Fork Polisher; and I do hereby declare the following to be a full, clear, and exact description of the same, reference being had to the accompanying drawings, forming a part thereof.

The leading feature of my design consists in the base or rubbing-surface having the shape of an oblong square surmounted by a cap having upwardly-inclined sides, on the top of which is a handle having inwardly-curved sides presenting in cross-section the appearance of a T-rail.

In the accompanying drawings, Figure 1 is a perspective of the knife and fork polisher, looking from its top; and Fig. 2, a perspective looking from the under side.

In the drawings the numeral 1 designates the base or rubbing-surface, which has the shape or outline of an oblong square. This base is surmounted by a cap 2, whose sides 3 incline or recede from the bottom upwardly. The handle 4 on top of the cap 2 has inwardly-curved sides 5 and presents in outline the appearance of a T-rail. The ends of the han-

dle 4 describe vertical lines, terminating back 30 from the opposite ends of the cap 2, so that the vertical ends of the handle and the horizontal top surface or plane of the cap which extends inwardly from opposite ends of the cap will meet and form a right-angled space 6 35 at opposite ends of the handle, as illustrated. A band 7 is extended around the sides and ends of the rubbing-surface and cap at the junction of those two parts and at a distance above the bottom face of the rubbing-surface. 40

The general effect of the shape or outline described is to present the appearance of a substructure of an oblong square surmounted by a cap whose sides incline inwardly from the vertical sides of the oblong square and 45 having on top a section of a T-rail, the point where the oblong square and the cap meet being bordered by an inclosing band.

I claim—

The design for a knife and fork polisher 50 shown and described.

In testimony whereof I affix my signature in presence of two witnesses.

HESSY S. ROSENSTOCK.
